UNITED STATES PATENT OFFICE

171,688

AUXILIARY CHUCK FOR SMALL TWIST DRILLS

Howard K. Chapman, Englewood, Colo.

Application February 13, 1953, Serial No. 23,620

Term of patent 14 years

(Cl. D54—13)

To all whom it may concern:

Be it known that I, Howard K. Chapman, a citizen of the United States of America, residing at Englewood, in the county of Arapahoe and State of Colorado, have invented a new, original, and ornamental Design for an Auxiliary Chuck for Small Twist Drills, of which the following is a specification, reference being had to the accompanying drawing, forming a part hereof.

In the drawing:

Fig. 1 is a perspective view of an auxiliary chuck for small twist drills showing my new design;

Fig. 2 is a top plan view thereof;

Fig. 3 is a side elevational view thereof; and
Fig. 4 is a bottom plan view thereof.

I claim:

The ornamental design for an auxiliary chuck for small twist drills, as shown.

HOWARD K. CHAPMAN.
